UNITED STATES PATENT OFFICE.

FRANK J. MINER, OF DETROIT, MICHIGAN, ASSIGNOR TO MINER ENGINEERING COMPANY, OF DETROIT, MICHIGAN, A CORPORATION OF MICHIGAN.

BLOWER OR PUMP.

979,324.

Specification of Letters Patent.

Patented Dec. 20, 1910.

Application filed February 26, 1909, Serial No. 480,227. Renewed June 29, 1910. Serial No. 569,579.

To all whom it may concern:

Be it known that I, FRANK J. MINER, a citizen of the United States of America, residing at Detroit, in the county of Wayne 5 and State of Michigan, have invented certain new and useful Improvements in Blowers or Pumps, of which the following is a specification, reference being had therein to the accompanying drawings.

10 In pressure blowers or pumps of the type wherein the blades moving in a closed casing are used to propel the air or fluid there-through, it is customary so far as known to me to employ either radial or propeller 15 blades secured to a rotatable shaft, or else a series of buckets carried by a flexible end-less belt or chain passing around and driven by suitable rotating members. In blowers of this type constructed in such manner, it 20 is difficult to prevent leakage around the blades, and, furthermore, in the belt or chain type, the stretching of the chain or belt, due to centrifugal force, is a very obnoxious feature.

25 This invention relates to a blower or pump whereby a series of conveyer blades moving at constant speed are adapted to impart velocity to the air or fluid propelled greater than the speed of the blades and whereby 30 leakage around the blades is to a large extent obviated and the destructive effects of centrifugal force are prevented.

The general structure of the device shown but not claimed in this application corre-sponds to that shown and claimed in my 35 prior application for blowers or pumps, filed May 30, 1908, Serial No. 430,433.

The invention consists in the matters hereinafter set forth, and more particularly 40 pointed out in the appended claims.

In the drawings, Figure 1 is a view in central transverse section of a blower or pump embodying features of the invention. Fig. 2 is a view, partially in section and par-tially in side elevation, on line $x-x$ of Fig. 45 1. Fig. 3 is a view in longitudinal section through the casing showing propelling blades in end elevation.

Referring to the drawings, 1 indicates a 50 drum or shell closed by side plates 2 detach-ably secured in place by suitable means and

provided with elongated central openings. Bonnets 3 secured over these openings, have alined bearings 4 in which a central drive shaft 5 is journaled, a pulley wheel 6 or like 55 means for applying power being secured on its outer end. A gear wheel 7 is secured on the shaft in each bonnet. A series of toothed racks 8 adapted to mesh with the gears are pivoted together at their ends to form an 60 endless chain in each bonnet by pivot bolts 9 extending transversely through the casing channel. Friction rolls 10 journaled on the pivot pins within the bonnets bear outwardly 65 against the face of a flange 11 which forms a cam path or track around the inner face of each bonnet, of such contour as to hold the racks in mesh with the drive gear 7. As a convenient detail of construction the 70 openings in the side plates 2 are slightly 75 smaller than and concentric with the cam path whereby a retaining ledge is formed which prevents endwise movement of the rolls 10.

Each pair of links in the chain is secured 75 rigidly to the base of a blade 13 extending transversely across the shell. The blade is preferably substantially triangular in cross-section and is adapted to completely fill the space between the rack and the inner periph-80 ery of the drum or shell. A plate 14 mov-ably secured in a slot in the apex of each blade is yieldingly projected against the inner periphery of the shell by suitably dis-85 posed springs 15. As a preferable mechani-cal construction a rib 16 of fiber or like 85 material is inset in the outer edge of each blade as a convenient means for eliminating friction and securing a tight joint with the shell and casing after the manner of a piston 90 packing ring.

The drum 1 has an inlet opening 17 con-nected by oppositely disposed channels 18 with intake ports 19 which are so disposed 95 as to be swept by each blade at the moment of its greatest acceleration due to the angular movement imparted to it by the rounded ends 20 of the cam path between parallel straight limbs 21 thereof. A discharge opening 22 in the casing, preferably dia-metrically opposite the inlet 17, is likewise 100 connected by suitably disposed channels 23

in the shell with discharge ports 24 each so disposed as to be swept by each blade at the moment of its commencing its forward angular movement.

5 Inasmuch as the links when they pass around the corners of the cam path open so as to leave a small space indicated at 25, washers 26 are placed upon the pivot pin 9 in such position as to seal these openings.

10 The blades are connected by or have hinged joints indicated at 27 and 28 of such a nature that they are tight and do not allow the air or fluid to escape by them.

By this arrangement of parts each blade 15 as it approaches an inlet port has an accelerated motion in reference to the blade ahead of it whereby the air or fluid trapped between it and the preceding blade is compressed and held under pressure while each 20 pair of blades are traversing either of the parallel limbs 21 of the cam path. As each blade commences its accelerated motion around the end of the cam path it rapidly uncovers an exhaust port and allows the 25 trapped or compressed air or fluid to escape through the outlet 22 thereby imparting a velocity to it higher than the traveling speed of the blades.

One of the chief advantages of the 30 construction is the rigid confinement of the propelling links by the cam path so that under high speed, centrifugal force does not tend to throw the blades outward toward the shell and they therefore can be made to closely fit, 35 thus greatly increasing the efficiency of the blower. Furthermore, the increased leverage due to the sweeping of the forward pivot in each link around the short turn of the path increases the compressing power at the 40 moment when it is most needed without materially affecting the load on the drive gear.

The faces of the wheels and links may be 45 made wide enough to transmit any desired power and the machine is simple in its construction and very effective.

Obviously, changes in the details of construction may be made without departing from the spirit of the invention and I do not 50 care to limit myself to any particular form or arrangement of parts.

What I claim as my invention is:—

1. The combination with a casing having 55 inlet and outlet ports, of a series of revolvable blades arranged within said casing and maintained in substantially parallel relation transverse to the casing to form a plurality of pockets successively communicating with said inlet and outlet ports, means for rotating said blades differentially to expand and contract said pockets when respectively in communication with said inlet and outlet ports, and means in the casing engaging the

blades adapted to define the motion thereof when operated by the rotating means. 65

2. The combination with a casing having inlet and outlet ports of revolvable blades articulated together and maintained in planes parallel to the axis of revolution within said casing to form a series of pockets 70 successively communicating with said inlet and outlet ports, rotatable driving means adapted to revolve the blades in the casing, and means in the casing engaging the blades and coacting with the driving means to move 75 the blades differentially whereby the said pockets are expanded and contracted when respectively in communication with said inlet and outlet ports.

3. The combination with a casing having 80 inlet and outlet ports of revolvable blades articulated together and maintained in planes parallel to the axis of revolution within said casing to form a series of pockets successively communicating with said inlet 85 and outlet ports and adapted to travel in a cam path in the casing whereby the said pockets are successively expanded and contracted when respectively in communication with said inlet and outlet ports, and a rotatable member engaging the blades adapted 90 to move them around the cam path.

4. The combination with a casing having inlet and outlet ports of revolvable blades having rigid bases articulated in an endless 95 chain within the casing whereby the blades form a series of pockets successively communicating with said inlet and outlet ports and adapted to travel in a cam path in the casing whereby said pockets are successively 100 expanded and contracted when respectively in communication with said inlet and outlet ports and a rotatable member adapted to successively engage and move the blade bases along the path, the blades being maintained 105 in planes parallel to the axis of revolution.

5. The combination with a casing having inlet and outlet ports, of revolvable blades having rigid bases articulated in an endless 110 chain within the casing whereby the blades form a series of pockets successively communicating with said inlet and outlet ports, a flange defining the motion of the bases and a rotatable member adapted to engage and drive the bases along the flange, the flange 115 and member coacting to successively expand and contract the pockets as they are respectively in communication with said inlet and outlet ports, the blades being maintained in planes parallel to the axis of revolution. 120

6. The combination with a casing having inlet and outlet ports, of revolvable blades, bases on the blades articulated in an endless chain within the casing whereby the blades form a series of pockets successively communicating with said inlet and outlet ports, 125

- each base having rack teeth on its inner side, an endless flange in the casing confining the blades to move along a predetermined path, and a rotatable gear engaging the base racks successively and forcing them along the flange, the gear and flange coacting to successively expand and contract the pockets as they are respectively in communication with said inlet and outlet ports. 5
7. The combination with a casing having inlet and outlet ports and a flange on its wall forming an endless cam path of revolute blades articulated in an endless chain at their bases which form toothed links therein, and a rotatable gear in mesh with the links, adapted to hold the blade bases against the cam flange and force them along it. 10
8. The combination with a casing having inlet and outlet ports, side walls with corresponding flanges on their proximate faces each forming an endless cam path, a gear rotatably secured in the casing, and revolute blades in the casing articulated in an endless chain engaging the gear and limited in its direction of motion by the flanges, the latter being adapted to alternately accelerate and retard the motion of each blade, and the casing having an exhaust port at the place of acceleration of the blades and an inlet port at the place of retardation. 15
9. The combination with a casing having inlet and outlet ports and consisting of an outer shell and parallel side plates closing the shell ends, a shaft journaled in the casing, and inwardly extending corresponding cam flanges on the side plates around the shaft, a series of blades articulated in an endless chain encircling the shaft within the flanges which are adapted to engage the blades near the inner ends, and a driving member on the shaft adapted to engage the blades and force them against and along the flanges with their outer ends sweeping the inner face of the shell, the cam flanges being adapted to accelerate the motion of each blade as it approaches an outlet port and recedes from an inlet port. 20
10. The combination with a casing having inlet and outlet ports and consisting of an outer shell, parallel side plates closing the shell ends, a shaft journaled in the casing and a pair of inwardly extending, corresponding flanges on the side plates around the shaft, of a series of blades articulated in an endless chain around the shaft within the flanges against which the blade bases are adapted to bear outwardly and a driving member on the shaft adapted to engage the blades and to force them outwardly and along the cam flanges, the flanges, driving member and blade coacting to hold the blades substantially perpendicular to and in contact with the shell throughout the transit of the cam flange, and to accelerate the motion of each blade as it approaches an outlet port and recedes from an inlet port. 25
11. The combination with a casing having inlet and outlet ports and consisting of an outer shell, parallel side plates closing the shell ends, a shaft journaled in the casing and a pair of inwardly extending, corresponding cam flanges on the side plates around the shaft, of a series of blades substantially triangular in section pivotally connected at their base corners, and adapted at their bases to bear against the inner faces of the cam flanges with the apices sweeping the inner face of the shell and a drive member on the shaft forcing the bases along the flange, the bases, flanges and driving member coacting to accelerate the motion of each blade as it approaches an outlet port and recedes from an inlet port. 30
12. The combination with a casing having inlet and outlet ports and consisting of an outer shell and parallel side plates closing the shell ends, a shaft journaled in the casing and a pair of inwardly extending, corresponding cam flanges on each side plate around the shaft, of a series of blades triangular in section, pivot pins each articulating the adjacent base ends of a pair of blades and engaging the inner faces of the cam flanges, and driving means on the shaft engaging the blade bases and forcing the pivot pins around the flanges, the driving means, flanges and pins coacting to accelerate the motion of each blade as it approaches an outlet port and recedes from an inlet port. 35
13. The combination with a casing having inlet and outlet ports and consisting of an outer shell, parallel side plates closing the shell ends, a shaft journaled in the casing and a pair of inwardly extending, corresponding cam flanges on the side plates around the shaft, of a series of blades substantially triangular in section and pivotally connected at their base corners, and adapted at their bases to bear against the inner faces of the cam flanges with the apices sweeping the inner face of the shell, a drive member on the shaft forcing the bases along the flange, the bases, flanges and driving member coacting to accelerate the motion of each blade as it approaches an outlet port and recedes from an inlet port, and a movable member in the outer end of each blade yielding coacting with the shell. 40
14. A casing with inlet and outlet ports, and having an outer shell, side plates closing the ends of the shell each provided with a central opening surrounded by an inwardly extending cam flange, a series of 45

blades having extended bases articulated at the ends in an endless chain, cam rolls at the base ends each bearing against the inner face of the proximate flange, rack teeth on the inner margins of the bases in the planes of the cam flanges, a shaft, and driving gears on the shaft engaging the adjacent bases, adapted to force the blades around

the flanges with the outer blade ends sweeping the inner face of the shell.

In testimony whereof I affix my signature in presence of two witnesses.
